UNITED STATES PATENT OFFICE.

WILLIAM L. LAUDAN, OF STERLING, COLORADO.

MEASURED-QUANTITY-CONTROL DEVICE.

Application filed July 31, 1924. Serial No. 729,880.

To all whom it may concern:

Be it known that I, WILLIAM L. LAUDAN, a citizen of the United States, residing at Sterling, county of Logan, and State of Colorado, have invented certain new and useful Improvements in Measured-Quantity- Control Devices; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a predetermined- quantity control device or pump, which is operated by the varying pressure within a chamber, and which delivers liquid in measured quantities to any desired place.

It is the object of this invention to produce a simple device that can be connected to the explosion chamber of an internal combustion engine or to the cylinder of an air compressor, which will function as a pump for transferring a liquid or other fluid from one container to another.

Another object of this invention is to produce a device that shall be adapted to transfer lubricating oil from an oil cup to the inside of an engine or air pump cylinder in such a manner that oil will enter constantly in measured quantities, thereby assuring constant lubrication.

Many attempts have been made to properly lubricate the cylinders of air compressors. With the exception of some complicated force feed mechanism, however, no satisfactory lubricating device for air compressors has been discovered.

My invention can be most clearly described and will be most readily understood when reference is had to the accompanying drawing, in which the preferred embodiment thereof is illustrated, and in which:

Fig. 1 is a diagrammatic, sectional view showing my improved pump attached to an internal combustion engine or air pump cylinder;

Fig. 2 is a view showing the device connected to an air pump or engine for delivering lubricating oil to the same;

Fig. 3 shows my device applied to an oil cup;

Fig. 4 shows an oil cup provided with a slightly modified form of my invention; and

Fig. 5 is a section taken on line 5—5, Fig. 2.

Numerical 1 designates a cylinder and 2 the reciprocating piston, which is operatively associated therewith. A pipe 3 is connected with the cylinder and extends to the pump 4. This pump consists of a body member 5 having two spaced, preferably parallel openings 6. These openings have their ends 7 of somewhat larger diameter at the point where the opening 6 connects with the openings 7. Annular shoulders 8 are formed, which are preferably chamfered or inclined so as to form valve seats. The upper enlarged chamber 7 on one side is connected to the lower 70 enlarged chamber 7 on the other side by a channel 9. Seated within each opening 6 is a double ended valve having valve portions 10 connected by a stem 11. The valve portions 10 are adapted to cooperate with the seats 8, but the stems 11 are of such length that only one valve can seat at a time. The stems are also of smaller diameter than the openings 6 so that liquid can flow through the opening while the stem is in place. In order to permit the valves to be assembled in the manner shown, the stems are made in two parts and threadedly connected. Plugs 12 are threaded into three of the chambers 7. 85 The plugs in the upper chambers have adjusting screws 13 associated therewith. These screws engage a cup 14, against which the upper end of the spring 15 abuts. When it is desired to increase the tension of the 90 springs, the screws 13 are turned inwardly. This compresses the spring so that it requires greater force to unseat the valve. A pipe 16 leads to the supply 17 and a second pipe 18 leads to the reservoir 19.

It is evident that if the piston 2 moves downwardly there will be a diminution of pressure within the cylinder. When the difference in the pressure within the cylinder and that of the circumambient air becomes sufficiently great, it will raise the valve 10 on the left of the pump (Fig. 1) and permit liquid to flow upwardly into the upper chamber 7. As the suction and the flow of liquid increases, the valve will close against the lower seat, which, of course, stops the flow. When the piston returns, it will compress the fluid in the cylinder, but before any compression takes place, the pressure will approach atmospheric. At 110 some point between the condition of suction

and compression within the cylinder, the spring 15 moves the valve to the position shown in the drawing. When the pressure becomes sufficiently great the fluid or liquid 5 will unseat the valve on the right (Fig. 1) and enter the pipe 18. As the pressure within the cylinder changes from below the above atmospheric, the above operation will be repeated, with the result that a liquid 10 will be transferred from 17 to 19. It is evident that until there has been sufficient oil raised from the supply 17 to fill the passage 9 and associated chambers 7 that pressure should not be admitted, since it will 15 only cause air to enter the pipe 18. At the same time, if the liquid should enter the pump faster than it can leave it, the liquid would soon accumulate and enter the pipe 3. To prevent this, I have provided a float 20 chamber 20 directly above the pump 4.

This chamber contains a float 21, which controls two valves 22 and 23. When the float chamber is empty, the valve 23 is closed, but when it is full the valve 22 is closed, while at some intermediate point both valves are open. The float operates to prevent air under pressure from entering the pump until the latter has been completely filled and the liquid has risen sufficiently 30 in the float chamber to raise the float. If, for any reason, more liquid should be sucked into the pump than can leave, then the float will finally rise sufficiently to close valve 22, which will effectively prevent 35 more liquid from entering until the level in the float chamber has fallen. The float will therefore serve to keep the pump full of liquid at all times and to prevent liquid from entering the cylinder. Although 40 I have shown the valve in the righthand opening 6 as a double one, this is not absolutely necessary, as the lower valve portion may be dispensed with without changing the operation to any great extent. If the 45 righthand valve is single instead of double, there will be very little danger of liquid accumulating in the pump.

When my device is to be used for supplying a lubricant to a cylinder, a somewhat 50 simpler device than that described may be employed. This simplified device is shown in Fig. 2, in which the pump is indicated by numeral 4A. The part 5 may be a cylindrical bar provided with a central axial opening 6A having enlarged chambers 7A at its ends. The pump has only a single double ended valve member, which is constructed and which functions exactly like the one shown on the right of the pump in 55 Fig. 1. The parts have been designated with the same numerals as corresponding parts in Fig. 1, each numeral having an A attached to indicate that they represent specifically different parts.

60 When the portion 2 reciprocates, it pro-

duces a suction on its downward stroke. This causes oil to flow from the supply 17. Only a limited amount of this oil will pass the valve on each stroke, as the valve seats against the lower valve seat a short interval of time after it opens. The length of time the passage past the valve is open depends somewhat upon the length of the valve and the tension of the spring 15, one or both of which must be altered until the 75 desired results are obtained.

In Fig. 3 I have shown my improved pump incorporated into an oil cup, which has a cup portion 24 having an internally threaded downwardly projecting nipple 25 that is connected to the cylinder 1 by means of a pipe 26. The cup has a cover 27 provided with an opening 28. Within the cup 1 place my improved control device consisting of a body member 29, which has a 80 tubular threaded end 30 that is threaded into the nipple 25. The opening 31 is connected by means of a transverse opening 32 with the enlarged chamber 33, which is connected by an opening 34 with a second enlarged chamber 35. The shoulders at the ends of the opening 34 are provided with beveled valve seats 36, which cooperate with a double ended valve constructed like those previously described. A screen 37 closes the 85 end of the chamber 35 and prevents dirt from entering. The action of this device is exactly the same as explained in connection with Fig. 2.

In Fig. 4 I show a slight modification. 100 In my control device is incorporated the part 38 that connects the nipple 25 with the cylinder. Member 38 is constructed almost exactly like that shown in Fig. 2 and differs from it principally in this, that the 105 spring 39 is under tension instead of under compression. The upper end of the spring is connected to a threaded pin 40 that passes through a support 41 that is threadedly secured to the end of member 38. A nut 42 110 cooperates with the pin 40. This device operates in precisely the same way as those shown in Figs. 1 and 2 and differs merely in this, that the spring is under tension instead of under compression.

115 Although I have described the above invention as being particularly adapted for use in connection with the lubrication of air compressors and have employed language that might imply that there must be 120 a variation in pressure which changes from above to below atmospheric, I want it understood that my device may be used in connection with steam engines both of the condensing and uncondensing type, as the 125 only requirement is that the pressure in the supply reservoir 17 shall be greater than the minimum pressure in the cylinder so that oil will flow upwardly through the check valve opening on the left (Fig. 1). 130

3

- If the supply reservoir is subjected to pressure, the tension of the spring 15 will have to be sufficient to hold the valve seated in spite of the same.
- 5 It will be apparent from the above description that I have invented a simple device that is especially well adapted to lubricate the cylinders of air compressors and other machines where there is a chamber 10 which is subjected alternately to pressures above and below atmospheric. When my device is constructed in the manner shown in Fig. 1, it can be used for a variety of purposes, but is especially well adapted for 15 use in connection with internal combustion engines for circulating oil and can be substituted for the ordinary oil pump. In connection with automobile engines having a splash oiling system, my device can readily be applied for the purpose of producing a positive circulation of oil, which will prevent damage in case the gravity circulation shall become inoperative for any reason.
- When constructed as shown in Figs. 3 25 and 4 the oil cups may be attached directly to an engine cylinder as readily as any simple oil cup and will provide positive constant lubrication.
- Having now described my invention, what 30 I claim as new is:
1. A pump for transferring liquid, comprising, in combination, a body member having two spaced openings having portions thereof of different diameters, a pair of 35 spaced valve seats formed in said openings at the point where the diameters change, a valve member for each of said openings, said valve members being each provided with two spaced valve portions adapted to cooperate with said valve seats, said valve 40 being of such length that it can contact with only one valve seat at a time, resilient means associated with each valve member for normally holding a valve portion against one of said valve seats, and means for connecting the enlarged portion of each of said 45 openings containing respectively the normally open and the normally seated valve, with a chamber having a pressure variation from below to above atmospheric. 50
2. A pump for transferring liquid, comprising, in combination, a body member having two spaced openings having portions thereof of different diameters, a pair of 55 spaced valve seats formed in said openings at the point where the diameters change, a valve member for each of said openings, said valve members being each provided with two spaced valve portions adapted to cooperate with said valve seats, said valve 60 being of such length that it can contact with only one valve seat at a time, resilient means associated with each valve member for normally holding a valve portion against one of said valve seats, and means for connecting the enlarged portion of each of said 65 openings containing respectively the normally open and the normally seated valve, with a chamber having a pressure variation from below to above atmospheric, said 70 means comprising a float valve adapted to close one of two openings.

In testimony whereof I affix my signature.

WILLIAM L. LAUDAN.
